UNITED STATES PATENT OFFICE

93,240

DESIGN FOR A PLATE OR SIMILAR ARTICLE

Benjamin F. Perkins, Holyoke, Mass.

Application June 1, 1934, Serial No. 52,010

Term of patent 3½ years

To all whom it may concern:

Be it known that I, BENJAMIN F. PERKINS, a citizen of the United States, residing at Holyoke, in the county of Hampden and State of Massachusetts, have invented a new, original, and ornamental Design for a Plate or Similar Article, of which the following is a specification, reference being had to the accompanying drawing, forming part hereof.

The figure is a plan view of a plate having a portion of the border design of my invention thereon. The remaining portion of the design extends around the plate in proper relation to the portion of design shown.

The design consists of a border for a plate or similar article consisting of concentrically arranged groups of squares. The squares of each group are arranged in rows and the adjacent group of squares are separated. The squares of one group are of a different size than those of another group and the adjacent squares are contrasting in color to create a checkerboard effect.

I claim:

The ornamental design for a plate or similar article as shown and described.

BENJAMIN F. PERKINS.
